STRAIGHT BEAM ADJUSTABLE JAW CLAMP

Arthur M. Beasley, Birmingham, Mich.

Application March 26, 1952, Serial No. 278,601

1 Claim. (Cl. 144—303)

1

This invention relates to clamps of the conventional C-type particularly as used for tool and die work, and in particular a clamp in which a jaw is slidably mounted in a holder with a pin slidably mounted in the holder and positioned to engage recesses in the shank of the jaw whereby the position of the jaw in relation to the holder is readily adjustable.

The purpose of this invention is to provide a clamp of the C-type in which the position of one jaw may be quickly set in relation to the other jaw or in relation to a holder.

In the conventional type of C-clamp a stud, threaded in one jaw of the clamp is positioned to coact with a gripping jaw and, particularly for tool and die work it is sometimes desirable to spread or retract the jaws. With the jaws provided on the arms of a solid body it is necessary to carry a series of clamps of different sizes. With this thought in mind this invention contemplates a clamp that is quickly adjustable from one size to another so that a single clamp is provided which performs the same function of, and consequently replaces, a set of clamps.

The object of this invention is, therefore, to provide means for mounting the shank of a jaw of a clamp in a holder forming a coacting jaw whereby the position of one jaw in relation to the other is readily adjustable.

Another object of the invention is to provide an improved clamp for tool and die work in which the shank of a jaw is retained in a slot of another jaw by a manually actuated frictionally held pin.

A further object of the invention is to provide an adjustable quick set clamp which is of a simple and economical construction.

With these and other objects and advantages in view the invention embodies a holder in the form of an arm having a screw threaded in the outer end with a slot extended through the inner end for retaining the shank of a jaw and a movable jaw having a shank with spaced openings in one edge thereof in which a pin frictionally held in the holder coacts with the opening in the shank of the jaw for retaining the jaw in adjusted position in relation to the holder.

Other features and advantages of the invention will appear from the following description taken in connection with the drawing wherein:

Figure 1 is a side elevational view illustrating the improved quick set clamp with parts broken away and shown in section.

Figure 2 is a sectional plan through the clamp taken on line 2—2 of Fig. 1.

2

Figure 3 is a section similar to that shown in Fig. 2 showing the end of the holder through which the shank of the jaw extends and illustrating a method of releasing the locking pin from the holder.

Figure 4 is a cross section through the mounting end of the holder taken on line 4—4 of Fig. 1.

Figure 5 is a detail showing an exploded view of the locking pin wherein the button and spring are extended therefrom.

Figure 6 is a sectional plan through the holder and shank of the jaw also taken on a plane corresponding with that of line 2—2 of Fig. 1 illustrating a modification wherein the jaw is provided with a tubular shank.

Figure 7 is a side elevational view showing the tubular shank illustrated in Fig. 6 extended through the holder and in which parts are broken away.

20 Referring now to the drawings wherein like reference characters denote corresponding parts the improved quick set clamp of this invention includes a jaw 10 carried by a shank 11 with a holder having a base 12 with a slot 13 through which the shank 11 extends and an arm 14 in the outer end of which a screw 15 is threaded, and the base 12 of the holder is provided with a pin 16 that is slidably mounted in an opening 17 in the base of the holder, the pin being positioned whereby the end thereof registers with openings 18 in the shank 11.

25 The jaw 10 is provided with a gripping surface 19 which is aligned with the screw 15 and with the parts in the position shown the screw coacts with the jaw for retaining objects with one object clamped to another.

30 The screw 15, which is provided with a handle 20 is threaded in an opening 21 in the end of the arm 14 and an additional opening 22 may be provided in the arm to reduce the weight thereof.

35 The pin 16 is slidably mounted in the opening 11 in the base 12 and the pin, which is provided with a head 23 is secured in the base by a button 24, positioned in an opening 25 in the base and adapted to extend into a slot 26 in the pin into which the button is urged by a spring 27. The pin 16 is also provided with an opening 28 that is positioned to register with an opening 29 in the base of the holder with the pin 16 drawn outwardly to the position shown in Fig. 3 wherein with the parts in this position a pin 30 may be inserted into the opening 28 through the opening 29 so that the button 24 may be held against the spring 27 to permit the pin 16 to be withdrawn.

40 The screw 15, which is provided with a handle 20 is threaded in an opening 21 in the end of the arm 14 and an additional opening 22 may be provided in the arm to reduce the weight thereof.

45 The pin 16 is slidably mounted in the opening 11 in the base 12 and the pin, which is provided with a head 23 is secured in the base by a button 24, positioned in an opening 25 in the base and adapted to extend into a slot 26 in the pin into which the button is urged by a spring 27. The pin 16 is also provided with an opening 28 that is positioned to register with an opening 29 in the base of the holder with the pin 16 drawn outwardly to the position shown in Fig. 3 wherein with the parts in this position a pin 30 may be inserted into the opening 28 through the opening 29 so that the button 24 may be held against the spring 27 to permit the pin 16 to be withdrawn.

The openings 18 are spaced through the intermediate part of the shank 11 of the jaw 10 and with the parts positioned as illustrated in Fig. 1 the pin 16 extends into one of the openings 18 for locking the jaw 10 in adjusted position. The extended end of the shank 11 may be provided with an opening 34 for positioning the clamp on a hanger or the like.

In the design illustrated in Figs. 6 and 7 the jaw is provided with a tubular shank 32 and spaced openings 33 are provided in one side of the shank to correspond with the openings 18 of the shank 11. The tubular shank 32 is provided with a keyway 320 and when the shank 32 is positioned in the shank opening 34 in the base 35 of a holder 36 a key 37 is positioned in the keyway 320 and in a slot 38 in the base. In this design the shank of the jaw is retained in adjusted positions by a pin 39, engaging one of the spaced openings 33. The pin 39 is similar to the pin 16 and the pin 39 is secured in the base of the holder by a button 40 positioned in a recess 41 and urged inwardly by a spring 42. The button 40 extends into a slot 43 in the pin 39 and an opening 44, similar to the opening 28 is positioned to register with an opening 45 by which the button 40 may be forced out of the slot 43, with a pin, such as the pin 38. The pin 38 is also provided with a head 46 similar to the head or handle 23 of the pin 16.

With the parts arranged in this manner the locking pin may readily be withdrawn to the position shown in Fig. 3 whereby the shank of the movable jaw is adapted to be moved through the slot in the base of the holder so that the distance of the jaw from the end of the screw 15 is readily adjustable. When the jaw is in the position desired the locking pin is moved inwardly thereby locking the jaw in the holder.

By this means the end of the screw 15 may be positioned against an object, the jaw 10 moved through the holder until it engages the opposite side of the object, and after inserting the pin 16 in one of the openings 18 the screw 15 is turned by hand to positively clamp the object against the jaw.

It will be understood that modifications may

be made in the design and arrangement of the parts without departing from the spirit of the invention.

What is claimed is:

- 5 In a quick set clamp, the combination which comprises a holder having a base with an arm extended therefrom and having an opening extended therethrough, a shank having a jaw extended from one end and having openings in 10 one edge slidably mounted in the base and extended through the said opening therein, an adjusting screw threaded in an extended end of the arm and positioned to coact with the jaw, a locking pin slidably mounted in the base of 15 the holder and positioned to extend into openings in said shank, means securing said pin in operative position in the holder, the means for retaining the pin in operative position in the holder comprises a spring actuated button positioned in 20 an opening in the holder and adapted to extend into an elongated slot in one side of the pin, said holder having an opening therein in alignment with said button and on the other side of said pin, said pin having an opening of smaller diameter than said last named opening in the holder positionable to register with said last named opening of the holder and said button, so that the button may be moved from the pin with a rod extended through the openings of the holder 25 and pin and engaging one end of the button in order to remove the pin completely from said holder.
